UNITED STATES PATENT OFFICE.

THOMAS W. MURPHY, OF PHILADELPHIA, PENNSYLVANIA.

LIQUID-ELEVATING DEVICE.

1,354,330.

Specification of Letters Patent. Patented Sept. 28, 1920.

Application filed April 8, 1920. Serial No. 372,193.

To all whom it may concern:

Be it known that I, THOMAS W. MURPHY, a citizen of the United States, residing in Philadelphia, Pennsylvania, have invented 5 Liquid-Elevating Devices, of which the following is a specification.

This invention relates to an apparatus for elevating liquids, especially acids and alkalies, from a low level to a higher one, and 10 has to do more particularly with an automatic valve device designed to act in conjunction with the necessary tanks, piping, etc., for utilizing compressed air for this purpose.

15 One object of the invention is to provide a relatively simple apparatus of the above noted type which shall eliminate or avoid the use of stuffing boxes and which shall be subject to a minimum of wear and tear by 20 reason of its movable parts being so arranged as to require but relatively limited movement under operating conditions.

It is further desired to provide a liquid elevating apparatus, which by reason of certain novel constructions and connections, 25 shall be capable of combining in one structure a liquid check and a valve for controlling the flow of both the high pressure—and the displaced air;—the arrangement of 30 parts being such as to materially reduce the cost of the apparatus.

Another object of the invention is to provide an air actuated device for intermittently raising bodies of liquid, which, even 35 when combined with the liquid check, shall be materially lighter in weight than has hitherto been the case with similar apparatus of the same class and capacity.

These objects and other advantageous 40 ends I attain as hereinafter set forth, reference being had to the accompanying drawings, in which,

Figure 1 is an elevation, to some extent diagrammatic, illustrating a liquid elevating system including my invention;

Fig. 2 is a vertical longitudinal section of the casing for the controlling valve and its associated parts;

Figs. 3, 4 and 5 are transverse sections on 50 the lines 3—3, 4—4, 5—5, Fig. 2; and

Fig. 6 is a fragmentary vertical section illustrating a slightly modified form of the ports and the associated structures for directing the displaced air in its flow through 55 the controlling valve member.

In Fig. 1 of the above drawings, 1 repre-

sents a supply reservoir or tank and 2 a receiving tank at a higher level than the tank 1, to which the liquid from the latter is to be delivered. For this purpose there is provided an inclosed blow tank 3 suitably supported at a level below the tank 1 in such a position that liquid may flow to it under the action of gravity through a conduit 4 in which is connected an automatic valve 60 whose casing is indicated at 50. This casing is preferably mounted on and its lower end communicates with, the blow tank 3 and it is also connected through a vent pipe 9 with the top of the supply tank 1, although it may be connected to any other point suitable for the free discharge of the air displaced from the blow tank.

In accordance with the preferred form of my invention, the valve casing 50 consists of 75 three suitably connected parts or sections 5, 6 and 7, of which the lowest is connected to the blow tank 3 and the topmost is connected to the conduit 4. The lowest section 7 of the casing has formed in it a vertical passage 10, at whose upper end is a conical seat 11 for coaction with a correspondingly formed plug or float 12 which serves as a valve member. Surrounding the upper part of the passage 10, in the present case concentrically therewith, is an annular channel 13 connecting with it through a suitable number of radial ports 14 and designed for connection at 15 with any suitable source of supply of air under pressure. In the present case, the two ports 14 open into the passage 10 on the conical seat 11 at points opposite to each other and equi-distant from the air inlet 15;—it being noted that said seat is formed by the inner ends of a number of 80 radially extending, more or less solid, arms or ribs which project into the enlarged upper end of the passage 10, and that the ports 14 open on these valve engaging faces.

In accordance with one form of my invention, the upper portion of the valve or float 12 is also conically formed as indicated at 16, and co-operates with a conical seat 17 formed in the casing section 6 concentrically with the passage 10 of the section 7. 100 This seat has formed in it a number of ports communicating with an annular channel 18 which connects with the entrance to the exhaust or vent pipe 9;—the casing sections 6 and 7 co-operating to form a chamber in 110 which the valve member 12 is vertically movable between two extreme positions. In

the lower of these it engages the seat 11 so as to close the ports 14, while in the upper position it engages the seat 17 and cuts off the flow of air into the channel 18 and exhaust pipe 9.

It is to be understood that the form and arrangement of the seat 17 with its ports may be widely varied without departing from my invention, and in Fig. 6 I have shown such a variation in which the casting section 6 is formed to provide a flat valve seat 17^a for coaction with the similarly flat upper end of the valve member 12^a. The annular port 18^a leading to the channel 18 opens on this flat seat through a number of holes and as before said valve member will prevent the escape of high pressure air when in its upper or raised position, while permitting relatively free and unrestricted discharge of air displaced from the blow tank when in its lower position.

A pipe 19 has its end suitably turned over as in Fig. 2 or is flanged as in Fig. 6, so as to be supported with said end at or adjacent the plane of junction of the casing sections 5 and 6, from which it extends down concentrically through the sections 6 and 7 and through the valve member 12 and passage 10 to a point substantially below the lower face of the section 7;—being so arranged as to prevent liquid flowing into the top of the valve casing 50 from reaching or acting on the top of the valve provided by the float or hollow plug 12. Said pipe not only passes loosely through the valve member 12 but likewise cooperates with the casing section 7 to provide an annular passage 10 for the displaced or exhausted air flowing from the blow case 3 to the exhaust ports 18^b leading into the channel 18.

In the top part of the section 5 of the casing which is formed with a passage 20 in line with the pipe 19, I provide an annular valve seat 21, below which are formed vertically extending passages 22 whereby under certain conditions liquid may pass around a check valve 23 mounted in said passage below said seat. This valve consists of a flat disk carried through vertical ribs 26 by a ring 25 which rests on the top face of the casing section 6 and supports said valve a short distance below the seat 21. It is to be understood however, that while in some cases I employ this check valve 23 as shown in Fig. 2, it may be omitted from the valve casing and this or any other desired type of check valve placed at any other suitable point in the system without departing from my invention.

While obviously the above described casing and valve members may be made of any desired material, I preferably construct them of lead or other non-corrodible sub-

stance when the apparatus is intended for elevating acids, alkalis or the like, for which use it is especially available owing to the absence of the stuffing boxes such as are necessary when pumps are employed and also because of the comparatively slight and limited movement required by its parts 12 and 23.

Under normal conditions the valve member 12 is seated in its lower position illustrated in Fig. 2 so as to close the ports 14 leading from the channel 13 and thus prevent flow of air under pressure into the chamber for the valve member 12, which however at all times is acted on by the upward force due to the pressure of said air.

When it is desired to transfer liquid from the tank 1 to the tank 2, I open a suitable stop valve 30 in the conduit 4 and permit liquid to flow from the former tank through said conduit into the valve casing 50. On entering this, such liquid strikes the part 24 of the check valve 23 and passes around it through the passages formed by the ribs 22, from whence it flows between the ribs 25 and into and through the pipe 19 to the blow case 3 without in any way acting on the valve member 12. The air displaced by the rise of this liquid in said blow case escapes through the passage 10 around the pipe 19 and thence between the latter and the valve member 12, through the ports 18^b Fig. 2, or through the ports 18^a Fig. 6, into the channel 18, from whence it flows through the vent pipe 9 to the top of the supply tank 1 or to any other point of free discharge.

The flow of liquid from the tank 1 continues until the blow case 3 is filled, after which said liquid rises through the passage 10 until it strikes the bottom of the hollow valve member 12 which is already acted on by the air under pressure in the ports 14. As a result of the impact upon it of this liquid, said valve member is raised from its seat upon the arms or ribs 11, thereby permitting air under relatively high pressure to enter the valve chamber through the ports 14, with the result that the valve member 12 is forcibly moved up into engagement with and held on its seat at the top of the casing section 6, thus cutting off the further escape of air into the channel 18 and vent pipe 9. The high pressure air also acts on the liquid in the lower part of the valve casing causing seating of the check valve 23 and forcing said liquid through the discharge pipe 8 into the receiving tank 2. The valve member 12 is held to its upper seat during this operation by reason of the unbalanced or excess air pressure on its lower face, so that flow of liquid from the blow case to the receiving tank continues until the former is so far

emptied that the compressed air escapes through the discharge pipe 8, which is usually carried down to or connected into the bottom of the blow tank.

- 5 Since the air ports 14 are much less in area than the annular passage 10 and the discharge pipe 8, the resulting sudden fall of pressure in the valve casing due to this escape of air through the pipe 8 allows the
 10 valve member 12 to drop so as to again close said air ports 14 and open the exhaust ports 18^b leading to the pipe 9. Since the pressure on the check valve 23 is also released, it opens and again permits liquid
 15 to flow from the supply tank to the blow tank, until this is filled. Thereupon the liquid rises in the valve casing 50, strikes and unseats the valve member 12, and is discharged into the receiving tank as before
 20 described.

It is particularly to be noted that by reason of the construction above described the liquid flowing into the casing can in no way interfere with the operation of the valve
 25 member 12, which regardless of said flow is raised from its seat by the impact of the liquid rising in the passage 10 and is moved to and held in a position closing the exhaust ports by the action of the high pressure air
 30 thus admitted. This action is assisted and rendered more certain by making the cross sectional area of the passage or channel 10 around the pipe 19 considerably greater than the area of the passage through the
 35 valves 12 so that this latter is forced up by the inflowing liquid which enters the space below it more rapidly than it can flow out of the same between the pipe 19 and said valve.

40 I claim:

1. The combination in a liquid elevating apparatus of a source of liquid; a blow tank; a casing connected to the blow tank; a valve in said casing for controlling the
 45 delivery of compressed air to the blow tank; a conduit extending through the valve for delivering liquid from said source to said blow tank; and a delivery pipe from said tank.
 50 2. The combination in a liquid elevating apparatus of a source of liquid; a blow tank; a casing having a pipe connected to said source and delivering to the blow tank; a valve operative on the pipe and controlling the delivery of compressed air to the blow tank; with a delivery pipe from said tank.
 55 3. The combination in a liquid elevating apparatus of a source of liquid; a blow tank; a conduit connecting said source and tank; an air controlling valve in said conduit; means for conducting liquid from the source through said valve to the tank; and a delivery pipe for the tank.

- 60 4. The combination in a liquid elevating

apparatus of a source of liquid; a blow tank; a conduit connecting said source with said tank and including a casing having an air outlet port and a compressed air inlet; with a single valve member in the casing 70 normally closing the compressed air inlet and movable into position to close the air outlet port during the flow of air from the inlet to the tank.

5. The combination in a liquid elevating 75 apparatus of a source of liquid; a blow tank; a conduit connecting said source with said tank and including a casing having an air outlet port and a compressed air inlet; a single valve member in the casing normally closing the compressed air inlet and movable into position to close the air outlet port during the flow of air from the inlet to the tank; with means for conducting liquid through the casing independently of 80 said valve.

6. The combination in a liquid elevating apparatus of a liquid source; a blow tank; a conduit including a casing for connecting said source with said tank; a check valve 90 in the casing for preventing flow therefrom toward the liquid source; and a valve in the casing for controlling the flow of air under pressure to the tank, said casing having an air exhaust passage also controlled by said 95 latter valve.

7. The combination in a liquid elevating apparatus of a liquid source; a blow tank; a casing connected both to said source and to said tank having a compressed air port 100 and an air exhaust port; a valve in the casing normally closing the compressed air port and positioned to be unseated by impact of liquid entering the casing from the tank, said valve being movable from a position closing the compressed air port to a position closing the air exhaust port; with means for conducting liquid from the source to the blow tank through said valve.

8. The combination in a liquid elevating 110 apparatus of a liquid source; a blow tank; means for connecting said source with the tank including a casing having a valve chamber; a conduit passing through said chamber; an annular valve operative on 115 said conduit; and seats in the chamber positioned to be engaged by the valve at the two extremes of its movement, for controlling the flow of air under pressure to the casing and the exhaust of displaced air 120 therefrom.

9. The combination of a casing having a liquid inlet, a liquid outlet and an inlet for compressed air; a valve member in the casing normally closing the air inlet; and means for conveying liquid through the casing from the inlet to the outlet through said 125 valve member.

10. The combination of a casing having a liquid inlet, a liquid outlet and an inlet for 130

compressed air; a valve member in the casing normally closing the air inlet; and means for conveying liquid through the casing from the inlet to the outlet through said 5 valve member, there being an air exhaust port in the casing positioned to be closed by said valve member under operating conditions.

11. The combination of a casing having a 10 liquid inlet, a liquid outlet and an inlet for compressed air; a valve member in the casing normally closing the air inlet; means for conveying liquid through the casing from the inlet to the outlet through said 15 valve member, there being an air exhaust port in the casing positioned to be closed by said valve member under operating conditions; with a second valve in the casing for preventing flow of fluid through the inlet when the valve is in position to close 20 said exhaust port.

12. A controlling device for a liquid elevating system consisting of a casing having an inlet and an outlet for liquid, an inlet 25 for compressed air and an outlet for displaced air; a valve member mounted in the casing to control the air inlet and air outlet; and means for preventing flow of liquid through the liquid inlet from affecting operation of the valve member.

13. A controlling device for a liquid elevating system consisting of a casing having an inlet and an outlet for liquid, an inlet 30 for compressed air and an outlet for displaced air; a valve member mounted in the casing to control the air inlet and air outlet; and means for leading liquid through

the casing in one direction independently of the valve member.

14. A casing having air inlet and exhaust 40 ports and an inlet and an outlet for liquid; a valve normally closing the air inlet port and movable into position to close the exhaust port; with a conduit extending through the valve in position to permit access of liquid thereto from one of the liquid 45 openings, while preventing such access of liquid from the other opening.

15. A controlling device for a liquid elevating system consisting of a casing having 50 a valve chamber, inlet and outlet passages for air and an inlet port for liquid; a conduit positioned to receive liquid from the liquid inlet passage and extending through the air outlet passage; with a valve in the 55 chamber placed to close the air inlet when in one position and to close the air outlet when in the other position.

16. A controlling device for a liquid elevating system consisting of a casing having 60 a through passage including two chambers; a check valve in one of said chambers for preventing liquid flow in one direction through the passage; a conduit leading from said chamber to the outside of the casing, 65 there being air inlet and exhaust ports opening into the second chamber; with a valve in the second chamber controlling the flow of air through said ports and positioned to be unseated by liquid entering the casing 70 through that part of the passage relatively distant from said first valve.

In witness whereof I affix my signature.
THOMAS W. MURPHY.
